(57) CLAIM

The ornamental design for a panoramic camera, as shown and described.

DESCRIPTION

FIG. 1 is a front perspective view of a panoramic camera according to the present design;

FIG. 2 is a rear perspective view of the panoramic camera of FIG. 1;

FIG. 3 is a top plan view of the panoramic camera of FIG. 1; FIG. 4 is a bottom plan view of the panoramic camera of FIG. 1;

FIG. 5 is a right elevational view of the panoramic camera of FIG. 1;

FIG. 6 is a left elevational view of the panoramic camera of FIG. 1;

FIG. 7 is a front elevational view of the panoramic camera of FIG. 1; and,

FIG. 8 is a rear elevational view of the panoramic camera of FIG. 1.

The broken lines shown in all views are for illustrative purposes only and form no part of the claimed design.
